UNITED STATES PATENT OFFICE

151,072

DESIGN FOR A HOG OILER

George J. Saffert, New Ulm, Minn.

Application November 8, 1945, Serial No. 123,579

Term of patent 3½ years

(Cl. D12—2)

To all whom it may concern:

Be it known that I, George J. Saffert, a citizen of the United States, residing at New Ulm, county of Brown, and State of Minnesota, have invented a new, original, and ornamental Design for a Hog Oiler, of which the following is a specification, reference being had to the accompanying drawing, forming part thereof.

Figure 1 is a perspective view of a hog oiler, showing my new design;

Figure 2 is a front elevational view of the same; and

Figure 3 is a side elevational view of the same.

I claim:

The ornamental design for a hog oiler, as shown.

GEORGE J. SAFFERT.
